UNITED STATES PATENT OFFICE.

MARGARET AVERA AND HARDY A. AVERA, OF LOS ANGELES, CALIFORNIA.

DESIGN FOR A SOUVENIR-SPOON.

43,494.

Specification for Design.

Patented Feb. 4, 1913.

Application filed October 31, 1912. Serial No. 728,944. Term of patent 7 years.

To all whom it may concern:

Be it known that we, MARGARET AVERA and HARDY A. AVERA, citizens of the United States, residing at Los Angeles, in the county of Los Angeles and State of California, have invented a new, original, and ornamental Design for Souvenir-Spoons, of which the following is a specification, reference being had to the accompanying drawing, forming part thereof.

The figure is a plan view of a souvenir spoon, showing our new design.

We claim:

The ornamental design for a souvenir-spoon as shown.

MARGARET AVERA.
HARDY A. AVERA.
